UNITED STATES PATENT OFFICE.

JOHN H. GAVIN, OF CHICAGO, ILLINOIS, ASSIGNOR TO THE L. WOLFF MANUFACTURING COMPANY, OF SAME PLACE.

DESIGN FOR A WASHBOWL AND SLAB.

SPECIFICATION forming part of Design No. 23,805, dated November 13, 1894.

Application filed September 4, 1894. Serial No. 522,138. Term of patent 14 years.

To all whom it may concern:

Be it known that I, JOHN H. GAVIN, a citizen of the United States, residing at Chicago, in the county of Cook and State of Illinois, have 5 invented and produced a new and original Design for a Washbowl and Slab, of which the following is a specification, reference being had to the accompanying drawing, forming a part thereof.

10 The drawing shows a perspective view of the wash bowl and slab embodying my design.

The leading feature of my design consists in the general shape and outline of the wash bowl and slab as a whole, the several members 15 or portions of the whole, to wit: the bowl portion, the vertical slab portion and the horizontal slab portion being so shaped as to form a single complete unitary design, as illustrated in the drawing.

20 In the drawing A is the bowl, and B its rim. C is the horizontal slab.

D is the vertical back slab and E E are the two vertical side or end slabs.

F F are the brackets and B' B' are the continuous rounded edge or outline given to the 25 outer marginal edges of the vertical back slab and the two vertical end slabs. This rounded rim or edge B' B' unites on easy curves with the curved rim B of the bowl, as is clearly indicated in the drawing.

30 The bowl A is of an oval form, and has on its outer surface at the central and lower portion thereof a series of wide and narrow pointed leaf-like decorations a a' extending centrally toward the center or outlet H. In 35 the main zone of the bowl between its rim B and the decoration a a' is a scroll-like decoration a², as illustrated.

I claim—

The design for a wash bowl and slab herein 40 shown and described.

JOHN H. GAVIN.
